UNITED STATES PATENT OFFICE.

WILLIAM COLUMBUS PITTS AND ROBERT H. HAINES, OF MEMPHIS, TENNESSEE.

COTTON SAMPLER.

Application filed January 21, 1921. Serial No. 438,971.

To all whom it may concern:

Be it known that we, WILLIAM COLUMBUS PITTS and ROBERT H. HAINES, citizens of the United States, residing at Memphis, in the county of Shelby and State of Tennessee, have invented certain new and useful Improvements in Cotton Samplers; and we do hereby declare the following to be a full, clear, and exact description of the invention, 10 such as will enable others skilled in the art to which it appertains to make and use the same.

This invention relates to new and useful improvements in attachments for cotton gins or condensers and relates more particularly to what will be hereinafter known as a cotton sampler, the main object of the present invention being the provision of a device to be applied to the chute of a condenser for 20 obtaining an average sample of each bale of cotton, after the same has been ginned and compressed and before it has been arranged in bales.

Another object of the present invention is 25 the provision of a device adapted to be applied to the chute of a condenser for obtaining samples of each bale of cotton after the same has been ginned, said device being operated from power derived from the compression rolls of the condenser, whereby it 30 can be readily operated to obtain a sample of each bale of cotton as it passes the condenser into the press.

With the above and other objects in view, 35 the invention consists in the novel features and construction, the combination and arrangement of parts hereinafter more fully set forth, pointed out in the claims and shown in the accompanying drawings, in 40 which—

Figure 1 is an end elevation of a condenser, illustrating the application of our improved cotton sampler attached to the chute of the condenser;

45 Figure 2 is a longitudinal sectional view, and

Figure 3 is a plan view, illustrating the relative positions of the rollers.

In the accompanying drawings, illustrating 50 our improved invention, the numeral 1 designates suitable frame work of a cotton condenser which supports the condenser 2 that condenses and compresses the cotton after being ginned and before being passed 55 into the press for baling. Extending outwardly from one side of the condenser 2 is

a lint flue 3, leading from the condenser, while the other side is provided with a chute 4, which conveys the compressed cotton from the condenser into the cotton press 5. At 60 the upper end of the chute 4 and adjacent the condenser 2, are the usual compress rolls 6, whereby the cotton from the condenser is passed through these rolls to be pressed into compact form before passing down the 65 chute into the press 5.

Our improved sampler, as illustrated in Figure 1, is supported beneath the chute 4 and includes a suitable casing 7 secured to the bottom of the chute by means of the 70 flanges 8 which are bolted or otherwise secured to the bottom board of the chute. Arranged transversely within the casing 7 are the two rolls 9 and 10, the roll 9 being provided with suitable spike members 11 which 75 are adapted to pass through a slot 12 in the bottom of the chute 4 upon the rotation of the roller whereby samples of the compressed cotton passing along the chute will be engaged by the members 11 and drawn 80 downwardly into the casing 7.

After the cotton is drawn into the casing 7 by means of the spike members 11, the roller 10, which is provided with a brush surface 13 will engage with the cotton on 85 the members 11 and remove the same therefrom into a sample box arranged within the casing 7 and in a suitable position whereby to receive the cotton from the brush 13.

The sample box which is generally indicated by the numeral 14, includes a casing bolted or otherwise secured to the bottom of the casing 7 and arranged beneath an opening in the bottom of the casing 7, whereby the samples of cotton which are removed 90 from the spike members 11 by the brush 13 will be thrown into the sample box. In order that samples from each bale of the cotton may be separately taken, a removable box member 15 is arranged within the casing 14 and after the samples have been taken from one of the bales, this box 15 is 95 removed and a new one inserted, so that samples from the next bale can be readily obtained.

One end of the casing 7 is provided with inclined converging walls 16, the lower wall forming a guide whereby the cotton from the brush 13 will be guided into the sample box 15. The inner ends of the converging 110 walls 16 are spaced apart to provide for an air escape from the casing 7. The ends of

the shafts which support the rollers 9 and 10 project outwardly beyond the casing 7 and also extend beyond the side portions of the chute 4 and the shaft which supports the brush roller 10 is provided with a sprocket 17 which is connected by means of a chain 18 to a suitable sprocket 19 mounted upon the outer end of one of the shafts of the compress rolls 6. The shaft of the roller 9 is provided with a pulley 20 connected by means of a belt 21 to a suitable pulley on the shaft of the roller 10 for conveying power from the shaft of the roller 10 to the roller 9.

15 It will be noted from the above description, taken in connection with the accompanying drawings, that we have provided a simple device adapted to be applied to the chute of a cotton gin or condenser whereby 20 samples of the cotton bale can be obtained before the same is pressed into its baled form. It is the general practice, at the present time, that in obtaining samples from a bale of cotton, the wrapper in which the 25 bale is wrapped is either cut or torn and samples of cotton taken from the bale at various parts thereof, so that the average grade of the cotton can be determined. This means considerable expense and waste in 30 the covering material for the bale and it is our main object to provide a device whereby the samples of cotton can be readily obtained before the same is baled, thus saving the trouble and expense of obtaining the 35 average samples after the cotton has been already baled.

What we claim is:

1. In a cotton sampler, the combination 40 with a chute disposed in an inclined position for the conveyance of compressed cotton having a slot in the bottom thereof, of a casing arranged beneath the chute and

embracing the slot, a roll mounted for rotation within the casing directly beneath the slot, spike members projecting from the 45 periphery of said roll and movable through the slot to engage the cotton passing through the chute for removing small portions therefrom, a second roll in the casing carrying brushes for removing the cotton from the 50 spike members, a removable sample box attached to the casing for receiving the portions of the cotton, inclined converging walls formed in one end of the casing, one of said walls forming a guide for directing 55 the cotton samples into the sample box and means for imparting movement to the rolls.

2. In a cotton sampler, the combination with a chute disposed in an inclined position for the conveyance of compressed cotton, 60 having a slot in the bottom thereof, of a casing arranged beneath the chute, a roll mounted for rotation within the casing, directly beneath the slot in the chute, spike members projecting from the periphery of 65 said roll and movable through the slot to engage the cotton for removing small portions therefrom, a second roll in the casing arranged in alignment with the first roll, with respect to the position of the casing, 70 brush members carried by the second roll for engaging the spike members to remove the cotton therefrom, a removable sample box attached to the exterior of the casing at the bottom thereof for receiving the portions of the cotton, inclined converging walls formed in one end of said casing, one of said 75 walls forming a guide for directing the cotton samples into the sample box and means for imparting movement to the rolls.

In testimony whereof we affix our signatures.

WILLIAM COLUMBUS PITTS.
ROBERT H. HAINES.
